UNITED STATES PATENT OFFICE.

ELEAZER KEMPSHALL, OF NEW YORK, N. Y., ASSIGNOR TO KEMPSHALL SUPPLY COMPANY, A CORPORATION OF NEW JERSEY.

SPINNING-ROLL.

1,074,505.

Specification of Letters Patent. Patented Sept. 30, 1913.

Application filed March 3, 1913. Serial No. 761,883.

To all whom it may concern:

Be it known that I, ELEAZER KEMPSHALL, citizen of the United States, residing at New York, in the county of New York and State of New York, have invented certain new and useful Improvements in Spinning-Rolls; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to improvements in composite cots or covers for spinning rolls, and the method of making the same.

The object of the invention is to provide a composite cot composed of an outer tubular binder of leather and an inner soft rubber tube, the initial diameter of which is slightly greater than the inner diameter of the leather binder, to provide a means for securing the leather and rubber together,

25 so that when the cot is slipped or forced on the hard roll, the cot will be frictionally held in operative position.

Another object of this invention is to provide an improved method of producing the

30 cot.

I am aware it is old in the art to form a cot of rubber and leather for a spinning roll, but in each instance known to me the rubber is vulcanized to the roll, and the leather

35 is rolled on the rubber, while others employ cement for binding the elements together. However, all such attempts are impractical from a commercial and practical standpoint, as they involve undue expense, and loss of

40 time in affixing the cots to the rolls.

So far as I am aware, no attempts have been made to first form the leather into an endless tube of a determinate diameter, and then fit the rubber tube in the leather, and

45 depend on the expansive resiliency of the rubber tube against the inner surface of the leather to form a means for securing the elements of the cot together, and at the same time form an effective means for securing

50 the cot on a spinning roll.

The invention also comprehends improvements in the construction and arrangement of parts which will be hereinafter described, and particularly pointed out in the claim.

55 In the drawings: Figure 1 is a perspective

view of my improved spinning roll cot. Fig. 2 is a similar view of the inner soft rubber tube. Fig. 3 is a similar view of the outer leather tubular binder. Fig. 4 is a similar view illustrating one of the steps in the method of forming the cot. Fig. 5 is a cross section of a spinning roll provided with one of my improved composite cots.

The numeral 1 indicates a soft rubber tube, and 2, an outer tubular leather binder which fits over the soft rubber tube. The rubber tube is vulcanized and preferably reinforced before it is applied to a roll, and before it is fitted with the leather binder. The initial diameter of the soft rubber tube is slightly greater than the interior diameter of the tubular leather binder, so that when the leather tube is fitted to the soft rubber tube the expansive resilience of the rubber against the leather will serve to secure the two elements together. Thus the composite cot is wholly made up, and the parts frictionally united to each other prior to being placed on a spinning roll. By thus forming the cot, the diameter of a roll is predetermined by the binder, for the latter is made in tubular form prior to assembling same with the rubber tube, and because of the initial diameter of the rubber being a trifle greater than the inner diameter of the leather, the rubber becomes compressed and the thin leather tube is stretched tightly around the rubber. The friction created between the rubber and leather is increased by confining and consequent compression of the rubber, hence the two elements are for all practical purposes so intimately associated with each other as to form one yielding body.

It is my purpose to so produce the composite cot that it can be conveniently applied to a roll in a mill by unskilled labor. Hence it is of the utmost importance that the leather and rubber be assembled to form a unit, so that when a cot becomes worn, no great amount of time and expense is incurred in supplying a new one.

The internal diameter of the rubber tube is slightly less than the external diameter of the hard roll 5, as shown by the dotted lines 6, in Fig. 5, consequently the rubber tube is slightly stretched and is also slightly radially expanded, the dotted lines 5^x connecting Figs. 2 and 3 indicating the relative

sizes of the tubes. I take advantage of the relative proportions of the roll and the rubber tube, to form a means of securing the cot in operative position. The roll is slightly 5 corrugated as shown at 8, so that when forcing the cot on the roll, the rubber becomes embedded in the grooves of the corrugations, due to the fact that the radial expansion is limited by the tubular leather binder. Thus 10 when a cot is forced on a roll, the rubber is compressed between the leather and the corrugated surface, which accomplishes a dual result, to wit:—The rubber grips the corrugated surface, and the tension on the tubular 15 leather binder is materially increased, for it is further stretched over the outer periphery of the rubber.

In the method of forming my composite cot, I provide a tubular leather binder, 20 formed from a flat strip, the ends being brought together and cemented. I also provide a soft rubber tube of slightly greater diameter than the interior diameter of the leather tube, and in fitting the tubes together, the soft rubber is creased or folded 25 to fit in the leather tube, as shown in Fig. 4. Then the rubber tube is permitted to expand to its normal shape within the leather, and the latter, which is very thin, becomes 30 stretched over the outer surface of the rubber and frictionally engages therewith.

I lay great stress on the fact that the rubber tube is vulcanized before it is associated with either the leather tube, or the spinning 35 roll, and I also emphasize the fact that the rubber and leather tubes are fitted over each other as an article of manufacture before applying the cot to the roll, for it is by this means I am enabled to absolutely make cots 40 of uniform diameter.

From experience it has been demonstrated that to attempt to roll or apply a flat strip of leather to the rubber, either before or

after its application to a roll, is both expensive and impractical, particularly in so far as being able to obtain a perfectly smooth and properly stretched leather surface is concerned. Therefore, I find it of first importance to first make the leather binder in tubular form before placing same on the 45 rubber tube. This is true for two reasons: First, I am able to accurately determine the diameter of the cot, and second, it affords the only successful and practical method of properly stretching the leather to obtain a 50 perfectly smooth and even surface. A cot constructed as described is frictionally held on the roll, and the elements constituting the cot are frictionally held to each other, consequently the cots can be economically manufactured. 55

After the cot is applied to a roll, I may run a hot tool around the edges, to embed the leather in the rubber.

What I claim is:

As a new article of manufacture, a composite cot for a spinning roll comprising a tubular leather binder and a previously vulcanized soft rubber tube fitted within the leather tube and having an initial exterior 70 diameter greater than the interior diameter of the leather tube, whereby the expansive resilience of the rubber tube against the inner surface of the tubular leather binder serves to form a means for securing the 75 leather to the soft rubber tube, the tubular leather binder determining the diameter of the cot.

In testimony whereof I have signed my name to this specification in the presence of 80 two subscribing witnesses.

ELEAZER KEMPshall.
